UNITED STATES PATENT OFFICE.

LIPA POLINKOWSKY, OF ANTWERP, BELGIUM, ASSIGNEE TO WESTERN ELECTRIC COMPANY, INCORPORATED, OF NEW YORK, N. Y., A CORPORATION OF NEW YORK.

CALL-DISTRIBUTING SYSTEM.

Application filed June 20, 1922. Serial No. 569,634.

To all whom it may concern:

Be it known that I, LIPA POLINKOWSKY, a citizen of Russia, residing at 14 Rue du Bastion, in the city of Antwerp, Belgium, have 5 invented certain new and useful Improvements in Call-Distributing systems (for which I have filed an application in Great Britain June 10, 1921, No. 16,037, 1921), of which the following is a full, clear, concise 10 and exact description.

This invention relates to telephone systems, and particularly to a call distribution system for uniformly distributing calls received from the subscribers of the system 15 over a number of operators' positions.

It is the object of the present invention to provide an improved system of this character.

In carrying out the invention it is proposed to improve the distribution of the calls 20 by classifying the different operators with regard to the reception of the calls according to their availability for service. According to this classification an operator may be 25 free, may have received one waiting call, two waiting calls, three waiting calls or more and the distributing system is so arranged that upon the initiation of a call this call is extended to an operator who may be 30 regarded as most available for service. For example, if certain of the operators have two waiting calls upon their position not yet attended to and the remainder only one waiting call, a call initiated during this 35 condition will be extended to an operator having only one waiting call. If the operators are equally loaded further calls are equally distributed over all the positions.

This equal distribution is, according to the 40 particular embodiment of the present invention hereinafter fully described, carried up to three waiting calls as this has been found sufficient for practical purposes, but it will be fully understood that the equal distribution may be effected up to any number 45 of waiting calls desired. Further, immediately a call is received upon an operator's position, this position is held unavailable for a definite period of time, determined by means hereinafter fully described, and during 50 this period of time no calls may be extended to this position under any circumstances whatever.

According to a further feature of the invention it is arranged that after a position has 55 received a definite number of waiting calls the position is classified as such and remains classified as having this number of waiting calls until all these calls have been cleared. In this way an operator who becomes over- 60 loaded is given an opportunity to clear her position of waiting calls and the subscribers waiting for the operator's attention will be attended to more quickly than if calls con- 65 tinue to arrive at this position.

In the practical embodiment of the invention hereinafter described first line finder switches are provided for connecting a calling line of a group of subscribers' lines. 70 These first call finder switches are divided into subgroups which are connected with different groups of second line finder switches. Each second line finder switch forms part of an operator's cord circuit, one 75 end of this cord circuit terminating in a second line finder switch, the other end in a first group selector.

According to a further feature of the invention the call distributing system consists 80 of relays only, in contrast with systems heretofore proposed employing automatic switches. The use of relays only ensures exceedingly rapid operation and avoids the faulty distribution obtaining in systems employing automatic switches due to the time 85 involved in the operation of the switches.

The invention will be fully understood from the following description of one specific embodiment taken in connection with the accompanying drawings. Fig. 1 shows dia- 90 grammatically a calling line and a first line finder and the controlling relays for a group of such finders.

Figs. 2 and 3 show a cord circuit terminating in a second line finder switch, a first 95 selector switch, and a called line.

Figs. 4 and 5 show the controlling apparatus located at the operator's position together with the relays effecting the equal distribution of the calls. The drawings should be placed with Figure 2 to the right of Figure 1, Figure 3 to the right of Figure 2, and Figures 4 and 5 below Figures 2 and 3 respectively, with the adjacent corresponding conductors in alignment.

The system described is of the well-known

semi-automatic type in which upon a line calling, the line is connected automatically by first and second line finder switches to an operator's cord circuit. A register choosing 5 switch associated with the cord circuit automatically operates to select an operator's registering and controlling mechanism which is then connected with the cord. The operator obtains the number of the desired 10 line from the calling subscriber and registers the designation of the line upon a keyboard which thereupon controls the operation of the registering and controlling mechanism or sender to determine the subsequent operation 15 of the selector switches in the extension of the call.

The first line finder switches, of which the brushes 26, 27, 28 and 29 of one are shown in Fig. 1, have a large number of contacts for example, sixty sets, in their banks and are, therefore, capable of accommodating this number of subscribers' lines which may be regarded as a group of subscribers. The number of first line finder switches serving 25 such a group of subscribers will be termed a group of first line finders and such a group is divided into subgroups, for example, three, connected with different groups of second line finders of which the brushes 30 253, 254, 255 and 256 of one are shown in Fig. 2 of the drawings. Such second line finders have a similar number of contacts in their banks, and are, therefore, capable of accommodating, say, sixty trunks extending 35 from the first line finders. The second line finder switch shown forms part of a cord circuit, the other end of the cord circuit shown in Fig. 3 terminating in a first selector switch, and the number of such cords 40 serving a number of first line finder switches may be termed a group of cords and three such groups may be termed a super-group. Each group of cords is in turn divided into 45 subgroups and each operator has at her disposal one or more subgroups of cords from a number of super-groups of connecting circuits. A sub-group of cords may consist, for example, of three cords. A group of operators 50 may be termed a team.

53 The call distributing relays shown to the left of Figure 4 determine that only the free first line finders of those sub-groups which have access to free second line finders of the cords associated with free operators' positions may be operated to search for a calling line. When all the operators' positions are 55 busy and further calls arrive, one waiting call is distributed to each operator's position. This equal distribution is extended up to a definite number of calls, in the particular example described, three.

60 It is believed that the invention is of such a character as will be fully understood from a description of the operation of the system. 65 It will be understood that the sequence

switch elements shown in the cord circuit Fig. 2 and Fig. 3 are all controlled in the well-known manner by the sequence switch 220. The numbers attached to the contacts indicate when these contacts are closed except those numbers attached to the local contact 257 which indicate the positions in which this is open. The timing sequence switch 320 indicated within the rectangle at the bottom of Figure 4 controls the elements 75 79 therein.

80 Each operator's position is provided with an operator's busy relay 303 Figure 4 which, when operated, determines that the free second line finders of the cord circuits associated with this position may hunt for a calling line and bring in a call upon the operator's position. The relay 303 controls the circuit of relays, such as relay 312, one of which is provided for each two sub-groups of second line finder switches associated with the operator's position. 85

89 When an operator is at her position a key is thrown or plug inserted which causes the energization of the operator's relay 300 this 90 circuit being traceable from battery, resistance 301, winding of relay 300, through the operator's transmitter 302 to earth. Relay 300, upon operating, closes the circuit for the busy control relay 303 which may 95 be traced from battery, through its winding, right-hand front contact and armature of relay 300, normally closed contacts of relay 304, upper right and left-hand contacts of element 306 of timing sequence switch 320, 100 which normally rests in position 6, 12 or 18 back contact 398, 385 and 371 and armature 397, 384 and 370 of relays 307, 308, 309 respectively to earth. The busy control relay 303, upon energizing, closes a locking 105 circuit for itself to earth through its contact 311, armature 310 and back contact 353 and armature 395 of relay 363 independently of the contacts of element 305 and the contacts of relays 307, 308 and 309 and also 110 closes a circuit for the relay 312 and other relays similar to relay 312 in parallel therewith. As before explained, one relay such as relay 312 is provided for each two sub-groups of second line finders and a number 115 of such relays are provided controlled by the relay 303 according to the sub-groups of the second line finders which have access to the operator's position illustrated in Fig. 5 of the drawings. Relay 303 also closes 120 a circuit for the timing sequence switch 320 which circuit may be traced from battery, winding of this timing switch, upper left-hand contact of element 353 thereof, contact 342 and armature 316 of relay 303 to earth. 125 The timing switch 320 thereupon moves from the position in which it has been resting, for example, position 18, into position 1, which is one of the operative positions of the switch, indicating that the operator is at 130

her position and ready to receive a call. A call may be received also in positions 7 and 13.

Upon a subscriber, for example, the subscriber A of line 1, 2, Fig. 1 initiating a call he removes his receiver and the line relay 3 is energized over the loop in the usual manner and closes a circuit for the calling relay 4, one of which is provided for each group of subscribers' lines. Upon the calling relay 4 energizing, a circuit is closed for the call helping relay 5 in an obvious manner and this relay, one of which is provided, for example, for every nine first line finders, closes a circuit for the sub-group relays, such as 6, one such sub-group relay being provided for example, for every three first line finders. The circuit for this relay 6 may be traced from battery, front contact 317, and armature 318 of relay 319, Figure 4, armature 10 and front contact 11 of relay 5, Figure 1, winding of relay 6, to earth. Relay 319 individual to a group of second line finder switches is energized whenever one of the second line finder switches of the cords is in its normal position, that is to say, its controlling sequence switch 220, Figure 2, stands in position 1, and a relay such as 312, Figure 4, is energized indicating that a call may be received upon an operator's position with which the second line finder is associated. The circuit for the relay 319 may be traced from battery, through its winding, front contact 321 and armature 322 of relay 312, lower left-hand contact of element 226 of sequence switch 220 in position 1, to earth. The relays 329 and 339 are similarly energized so long as a cord circuit is available and an operator's position to which they have access may receive a call.

The relay 6, upon energizing, closes the circuit of the power magnets of the first line finders in this sub-group, the brushes 26, 27, 28 and 29 of one of which are illustrated in Fig. 1. This circuit may be traced from battery, armature 14 and back contact 15 of relay 16, armature 17 and back contact 18 of relay 19, winding of the power magnet 20, springs 21 and 22 of jack 23, contact 24 and armature 25 of relay 6 to earth. The power magnet 20 thereupon operates to rotate the brushes 26, 27, 28, 29 in search of the calling line and when this is found the test relay 30 energizes in the well-known manner due to the potential on the test terminal, and in turn causes the energization of the relay 19 which is of low resistance and causes the calling line to test busy to other switches. Relay 19, upon energizing, opens the circuit, before traced, of the power magnet 20 thereby bringing the brushes 26 to 29 to rest upon the contacts of the calling line and closes

the circuit for the holding magnet 31 of the first line finder, which circuit may be traced from battery, armature 14 and contact 15 of relay 16, armature 17 and front contact 32 of relay 19, winding of holding magnet 31 and winding of the calling relay 33 of the second line finder switches to earth. The connection of the low resistance test relay 19 in parallel with the winding of the calling relay 4 causes this relay 75 to deenergize thereby deenergizing the relays 5 and 6 and bringing all the other first line finders which are searching for the calling line to rest. The holding magnet 31 operates to hold the brushes in position in 80 contact with the contacts of the calling line in the well-known manner.

One calling relay, such as relay 33, is provided for each group of second line finders and this relay, upon energizing as before 85 described, closes the circuit of its helping relay 34 in an obvious manner. Relay 34 upon energizing closes the circuit for the line relay 230 and relay 231 of the selector switch of the cord circuit shown in Fig. 2 90 and this circuit may be traced from battery, armature 35 and front contact 36 of relay 34, contact 332 and armature 333 of relay 312, Figure 4, lower left and lower right-hand contacts of element 236 controlled by 95 the sequence switch 220, winding of relay 230, upper left-hand contacts of element 238, back contact 239 and armature 240 of the test relay 241, lower left-hand contact of element 242, to earth. Relay 231 is energized in parallel with the relay 230, this circuit being as before described as far as the element 236 when it may be traced from the upper right-hand contact of this element, winding of the relay 231, lower right-hand contact of spring 243, contact 244 and armature 245 of relay 246 to earth. The relay 231, upon energizing, locks itself to earth through its contact 261 and armature 260. A circuit is closed for the power magnet 247 of the second line finder switch which may be traced from battery, winding of power magnet 247, lower left-hand contact of element 248, front contact 249, and armature 250 of relay 230, front contact 110 251 and armature 252 of relay 231 to earth. The power magnet 247 thereupon operates to cause the brushes 253, 254, 255 and 256 of the second line finder to rotate in search of the trunk extending from the first line 115 finder switch and when this trunk is found the test relay 241 is operated in the usual manner to open the circuit of the line relay 230 which in turn deenergizes and opens the circuit of the power magnet 247 thereby 120 bringing the wipers to rest upon the terminals of the desired trunk line.

Upon the relay 230 deenergizing a circuit is closed for driving the sequence switch 220 of the cord circuit out of position 1. This 130

circuit may be traced from battery, winding of sequence switch 220 and its local contact 257, right-hand lower contact of element 258, back contact 259 and armature 250 of relay 230, contact 251 and armature 252 of relay 231 to earth. The sequence switch 220 thereupon moves from position 1 and under the control of its local contact moves into position 3 where 10 it comes to rest. In this position a circuit is closed for the register selecting sequence switch 262 and this switch thereupon operates in the well-known manner to select an idle registering mechanism not shown. The 15 contacts shown below the broken line in Figures 2 and 3, are controlled by sequence switch 262, the leads 200, 201, 202, 203, 205 and 206 extending to a registering mechanism of a character well known in the art 20 adapted to be operated to record the designation of the called line.

When the second line finder switch brings in a call the incoming call relay 363 at the operator's position is energized over a circuit extending from battery, winding of relay 363 contacts of key 330, holding magnet 207 of the second line finder switch, upper left and lower right-hand contacts of element 258, back contact 259 and armature 250 of relay 230, contact 251 and armature 252 of relay 231 to earth. Relay 363 opens the circuit before traced for the relay 303 at its back contact 356. Relay 303 thereupon deenergizes and opens the circuit of 35 the busy position relays such as 312, and the deenergization of these relays determines that no further calls for the time being may be received upon the operator's position. Relay 303 upon deenergizing closes the circuit for the timing sequence switch 320 which may be traced from battery, winding of this sequence switch, upper right-hand contact of its element 353, contacts of key 314, back contact 315 and armature 316 of 40 relay 303 to earth. The timing sequence switch 320, which it has been assumed to be standing in position 1, thereupon leaves this position and under the control of its local contact 313 moves into position 2. In position 2 a circuit is closed for the timing relay 335 which may be traced from battery, winding of the relay, lower right and left-hand contacts of element 305, interrupter 336 to earth. The interrupter 336 45 is arranged alternately to open and close the circuit of the relay 335 and upon its first energization a circuit is closed for the timing sequence switch 320 which may be traced from battery, through its winding and local contact 313, lower left-hand contact of element 353, front contact 337 and armature 338 of relay 335 to earth. The timing sequence switch 320 thereupon leaves position 2 and under the control of its local contact 313 50 moves into position 3. When the interrupter

reaches a position in which the circuit of the relay 335 is open this relay deenergizes and a circuit is closed through the armature 338 and the back contact 343 of the relay for the timing switch 320 which thereupon 70 moves into position 4. In this manner the sequence switch 320 moves step-by-step under the control of the interrupter 336 and the relay 335 until position 6 is reached. In position 6 of the sequence switch 320 the 75 energizing circuit before described for the relay 303 is again prepared at the upper left-hand and right-hand contact of element 305 and if the register choosing sequence switch 262 has selected a register mechanism the 80 relay 303 energizes and closes the circuit of the relays 312 so that further calls may be received upon the operator's position provided there is a free cord having access thereto. 85

While the sequence switch 220 is in position 3 during the time the register choosing sequence switch 262 is searching for an idle registering mechanism the relay 309 of the operator's equipment is energized in 90 a circuit extending from battery, winding of relay 309, lower left-hand contact of element 226, to earth. Relay 309, upon energizing, opens the energizing circuit of the relay 303 so that relay 303 cannot be energized 95 again, although the timing sequence switch 320 is in position 6, 12 or 18, until an idle register has been found and the relay 309 deenergized by the movement of the sequence switch 220 from position 3. The deenergized condition of the relay 303 causes relay 312 to remain deenergized in turn and prevents any further calls coming in to the operator's position except as hereinafter described. 100

When the sequence switch 220 reaches position 2 a circuit is closed from battery, calling lamp 323, Figure 4, lower right and upper left contact of element 232, Figure 2, to earth. The calling lamp glows, indicating to the operator that a call has arrived upon her position. When the register choosing sequence switch 262 finds a free register or sender the sequence switch 220 moves to position 4 and in this position the interrupter 233 is connected in series with the calling lamp 323 so that the lamp is then flashed intermittently. When the sequence switch 220 moves from position 3 the circuit before traced for the relay 309 is opened 110 at the lower left-hand contact of the element 226 so that this relay is deenergized. While the relay 309 was energized the first waiting call lamp 375 is energized in a circuit extending from battery, lamp 375, contact 115 376 and armature 377 of relay 308, contact 378 and armature 370 of relay 309 to earth. The lamp 375 indicated that a call had arrived and a register was being hunted for. 120

If a further call is initiated during the 130

time the relay 309 is energized, the call will be diverted from the operator's position shown and will be received at some other operator's position provided there is such a position free and available. Should, however, all the cords of a super group be held busy due to the deenergization of the relay 303 at each operator's position the relays 319, 329 and 339 will be deenergized. Upon the energization of the relay 5, when a further call is initiated during this condition a circuit is closed from battery, front contact 42 and armature 43 of relay 5, Figure 1, armature 345 and back contact 344 of relay 319, Figure 4, armature 347 and back contact 346 of relay 329, armature 348 and back contact 349 of relay 339, windings of relay 340 and 341 to earth. Relay 341, upon energizing, by closing its armature 359 and front contact 381 provides an alternative energizing circuit for the relay 303 to that provided through the armature 370 and contact 371 of the relay 309 and if there is a cord circuit available, that is, if there is a cord circuit having its sequence switch 220 standing in position 1, a circuit is closed for the relay 303 which may be traced from battery, through its winding, contacts of relay 300 and relay 304, upper right and left-hand contacts of element 305, assumed to have been driven from position 1 to position 6, contact 398 and armature 397 of relay 307, contact 385 and armature 384 of relay 308, armature 359 and front contact 381 of relay 341, back contact 372 and armature 322 of relay 312, lower left-hand contact of element 226, to earth.

Relay 303 thereupon energizes and closes a circuit for the relays 312 so that a further call may be received upon the operator's position, upon the energization of relay 34, Figure 1, although a call already needs attention thereupon. A second line finder switch thereupon operates to connect with the trunk extending from the first line finder switch which has connected with the calling line and the relay 363 at the operator's position is energized as before described and as it is assumed that the relay 309 is still energized owing to the first waiting call not having been connected with a registering mechanism, a circuit is closed for the second waiting call relay 308 which may be traced from battery, armature 390 and front contact 391 of relay 309, winding of relay 308, back contact 374 and armature 393 of relay 380, contact 394 and armature 395 of relay 363 to earth. The relay 308, upon energizing, opens the circuit of the first waiting call lamp 375 and closes the circuit of the second waiting call lamp 386, which circuit may be traced from battery, lamp 386, back contact 388, and armature 387 of relay 307, front contact 389, and armature 377 of relay 308, contact 378 and

armature 370 of relay 309 to earth. The second waiting call lamp 386 thereupon glows and indicates to the operator that a second waiting call has arrived upon her position.

The second waiting call relay 308 upon energizing also opens, at its armature 384 and contact 385, the circuit of the relay 303 so that the circuit of this relay is now opened at two points, that is, at contacts 385 and armature 384 controlled by relay 308 and at contact 371 and armature 370 of relay 309. If all the other operators' positions are loaded to an equal extent and another call is initiated, the relays 319, 329 and 339 will be deenergized as before described. The energizing of the relay 5 upon the initiation of this further call will therefore cause the energization of the relays 340 and 341 as before described and relay 341 will, by closing armature 359 and 381, provide an alternative path for the energizing circuit for the relay 303 to the circuit extending through the armature 370 and contact 371 of relay 309. This alternative path, however, is unable to complete the energizing circuit of the relay 303 as its circuit is opened as explained at the contact 385 and armature 384 of the second waiting call relay 308. The relay 312 remains deenergized and therefore does not cause the energization of the relay 319 which in turn maintains the relays 340 and 341 energized. The relay 340 closes the circuit of the slow-to-energize relay 350 which may be traced from battery, winding of relay 350, contact 351 and armature 352 of relay 340 to earth. The relay 350 attracts its armature a short time after its circuit is closed so that a circuit is now closed for the second pair of distributing relays 354 and 355 which may be traced from battery, contact 42 and armature 43 of relay 5, Figure 1, armatures 345, 347, 348 and back contacts 344, 346 and 349 of relays 319, 329 and 339 respectively, contact 366 and armature 324 of relay 350, windings of relays 354 and 355 to earth. The relay 355 upon energizing, by closing its contact 358 and armature 357 shunts the contact 385 and armature 384 of relay 308 so that now the relay 303 may be again energized over the circuit before traced but including the armature 357 and contact 358 in place of the contact 385 and armature 384 of the second waiting call relay 308.

The relay 303 upon energizing energizes the relay 312 and provided there are cord circuits free the second line finder switches thereof will operate, upon the energization of the relay 34, to search for the trunk extending from the first line finder switch which has found the calling line. When a second line finder switch finds the trunk and the relay 363 is energized as before de-

scribed, a circuit is closed for the third waiting call relay 307 which may be traced from battery, armature 390 and contact 391 of relay 309, winding of relay 307, front contact 392 and armature 393 of relay 380 (relay 380 having been energized upon the energization of relay 308 over a circuit from battery, armature 390 and contact 391 of relay 309, winding of relay 308, contact 369 and armature 396 of relay 308, winding of relay 380 to earth) contact 394 and armature 395 of relay 363 to earth. The relay 307 upon energizing closes a circuit from battery, third waiting call lamp 399; contact 334 and armature 387 of relay 307, contact 389 and armature 377 of relay 308, contact 378 and armature 370 of relay 309 to earth. The lamp 399 glows and indicates to the operator that a third waiting call has arrived upon her position.

The relay 307, upon energizing, opens the circuit of the relay 303 at a third point, namely at its contact 398 and armature 397. If therefore a further call is initiated and the energization of the distributing relays 340, 341, 354 and 355 is unable to effect the energization of the relay 303, the slow-to-energize relay 360 is energized by a circuit closed through contact 361 and armature 362 of relay 354. The relay 360 extends the circuit before traced from battery, contact 42 and armature 43 of relay 5, armatures 345, 347 and 348 and contacts 344, 346 and 349 of relays 319, 329 and 339 respectively, contact 366 and armature 324 of relay 350, contact 364 and armature 325 of relay 360, winding of relay 365 and 326 to earth. Relay 326 by closing armature 367 and contact 368 provides a shunt for the contact 398 and armature 397 of relay 307 so that further calls may be received provided there is a free cord by the energization of the relay 303 even although each position has three waiting calls thereon. Such further calls, however, will not be equally distributed over the operators' positions, the even distribution according to the specific method described of carrying the present invention into effect being up to three waiting calls only, which is sufficient for all practical purposes. Upon the relay 307 energizing it closes a locking circuit for itself through its armature 306 and contact 327, this locking circuit being controlled by the relay 309 at its contact 391 and armature 390 so that the relay 307 remains energized until the register sequence switch ceases to search for a register, that is, until there are no further waiting calls upon the operator's position. In this way the operators' positions which have received three waiting calls remain classified as having this number of waiting calls

thereupon, the third waiting call lamps 399 being lit, until all the calls thereupon have been cleared, which will be indicated by the relay 309 deenergizing. Further, by the waiting call lamps provided the condition of any particular operator's position may be ascertained immediately, a supervisor being informed whether the position has one, two or three waiting calls thereupon.

It will be seen that a very efficient call distribution system has been provided. The use of relays only causes the system to act exceedingly quickly effecting an even and accurate distribution of the calls.

What is claimed is:

1. In a call distribution system, a plurality of operators' positions, a plurality of cord circuits at each of said positions, means for extending calls to said cord circuits, relays individual to each operator's position for marking the said position as busy and for barring the further extension of calls to other cord circuits on the same position while a call remains unanswered, means responsive thereto for maintaining said artificial busy condition for a predetermined length of time, relays for marking said cord circuits as busy after calls extended thereto have been answered, means responsive to the number of unanswered calls on each of said operators' positions for measuring the degree of availability of each of said positions, and means for extending additional calls to said cord circuits in the order of the availability of said positions.

2. In a call distribution system, a plurality of operators' positions, a plurality of cord circuits at each of said positions, means for extending calls to said cord circuits, relays individual to each operator's position for marking the said position as busy and for barring the further extension of calls to other cord circuits on the same position while a call remains unanswered, means responsive thereto for maintaining said artificial busy condition for a predetermined length of time, relays for marking said cord circuits as busy after calls extended thereto have been answered, means responsive to the number of unanswered calls on each of said operators' positions for measuring the degree of availability of each of said positions, means for indicating the number of unanswered calls on each of said positions, and means for extending additional calls to said cord circuits in the order of the availability of said positions.

In witness whereof, I hereunto subscribe my name this 1st day of June A. D., 1922.

LIPA POLINKOWSKY.
